UNITED STATES PATENT OFFICE.

ROBERT L. HOGG, OF CHARLESTON, SOUTH CAROLINA.

ENGINE-STARTER.

1,270,160.

Specification of Letters Patent. Patented June 18, 1918.

Application filed June 5, 1917. Serial No. 172,997.

To all whom it may concern:

Be it known that I, ROBERT L. HOGG, a citizen of the United States, residing at Charleston, in the county of Charleston and 5 State of South Carolina, have invented certain new and useful Improvements in Engine-Starters; and I do hereby declare the following to be a full, clear, and exact description of the invention, such as will 10 enable others skilled in the art to which it appertains to make and use the same.

This invention relates to starters for internal combustion engines and more particularly to starters especially adapted for 15 use on internal combustion engines for automobiles by reason of its frequent necessity in the use of automobiles for the performance of the starting operation.

The primary object of the invention is the 20 provision of spring means for turning over the internal combustion engine a sufficient number of times to insure the firing of the initial charge of mixture taken into the cylinders of the engine, so that the automatic starting of the engine is insured.

Another object of the invention is the 25 provision of means for automatically connecting the spring means to the engine, after the same has fully started, so that the spring means will be automatically reset for 30 its next operation.

A still further object of the invention is the provision of means controlled by the contraction and expanding of the spring 35 during its winding and unwinding movement for connecting and disconnecting the same to the crank shaft of the engine so that the spring means will be automatically rewound for its next operation.

40 A still further object of the invention is the provision of a starter for an automobile internal combustion engine, which is simple in construction, durable and reliable in operation and can be manufactured and placed 45 upon the market at a reasonable cost.

With these and other objects in view, the invention consists in the novel construction, arrangement and formation of parts, as will be hereinafter specifically described, claimed

and illustrated in the accompanying drawings, forming a part thereof, in which

Figure 1 is a horizontal longitudinal section taken through the improved starting device,

Fig. 2 is a vertical longitudinal section 55 through the improved device, and

Fig. 3 is a detail section taken on the line 3-3 of Fig. 2.

Referring to the drawings in detail wherein similar reference numerals designate corresponding parts throughout the several views, the numeral 1 generally indicates the improved engine starter which includes the cylindrical casing 2 having the driving shaft 3 rotatably mounted therein. 60 The cylindrical casing 2 is formed of two substantially semi-cylindrical sections 4 and 5 each of which include curved end walls, and semi-cylindrical side walls. The meeting edges of the sections 4 and 5 are provided with projecting lugs 6 which are apertured to receive suitable fastening elements which are adapted to hold the sections together. 70

The driving shaft 3 is journaled in suitable bearings 7 in one end of the casing and in a bracket 8 which consists of a quadrant shaped plate extending up from the bottom of the casing at one side of the vertical axis of the casing to the horizontal axis of the 80 casing and has a detachable upper bearing plate 9 secured thereto. The inner end of the driving shaft 3 is rotatably received for independent rotation in the recess 10 formed in the driven shaft 11, which is journaled in 85 the opposite end of the casing 2 in suitable bearings 12. The rotative force to drive the driving shaft 3 originates at the coil spring 13, which has one end secured to the shaft 3 and the opposite end to the casing 2 as at 90 14. A pawl 15 is pivotally mounted intermediate its ends to the bracket 8 by means of a pivot pin 16 and engages the ratchet wheel 17 which is secured to the shaft 10 and prevents the spring from unwinding 95 and rotating the driving shaft 3. A suitable coil spring 18 is secured to the free end of the pawl 15 and to the bracket 8 and nor-

mally holds the pawl in engagement with the ratchet wheel 17.

The shaft 3 has a sliding clutch section 19 keyed thereto which is adapted to move forward into locking engagement with the rigid clutch section 20 keyed to the inner end of the driven shaft 11.

An arm 21 having a forked shaped end 22 is secured to the rotatable collar 23 fitted 10 in the groove 24 in the sliding clutch section 19 and has its lower end keyed to the stub shaft 24, which is positioned adjacent the bottom of the casing at right angles to the arm 21 for rocking movement and extends 15 out of the casing 2. A crank 25 is secured to the free end of the stub shaft 24 for rocking the same and a rod 26 extends from the free end of the same to the foot board of an automobile (not shown) and is connected to a suitable spring actuated pedal 20 (not shown) so that when the foot pedal is depressed the crank 25 will be rocked which will slide the clutch section 19 into locking engagement with the clutch section 20 for 25 the locking shafts 3 and 11 for synchronous movement. An arm 27 is pivotally secured to the arm 21 for movement therewith by means of a pivot pin 28 which extends through a slot 29 formed in the arm 21. 30 The arm 27 has its outer end enlarged to form a slanting surface which is adapted to engage the free end of the pawl 15 so that when the clutch section 19 is moved into engagement with the clutch section 20 by 35 the arm 21 the same will slide the arm 27 toward the clutch so that the enlarged end 30 of the arm 27 will engage the free end of the pawl 15 and throw the same out of engagement with the ratchet wheel 17, so 40 that the spring 13 will be free to rotate the shaft 3. The arm 27 is slidably supported in the casing by means of the plate 8 and a similar plate 30 which is secured to the bottom portion of the casing in spaced relation to the plate 8.

A gear wheel 31 is rotatably mounted upon the driven shaft 11 for independent movement and meshes with a similar gear 32 keyed to the counter shaft 33 which is 50 journaled in a suitable bracket 34 and in the plate 8 and is held against movement by the upper bearing section 9 of the plate. A gear wheel 35 is keyed to the opposite end of the counter shaft 33 and meshes with 55 a gear 36 keyed to the stub shaft 37 journaled in the plate 8, which in turn meshes with the gear 38 keyed to the driving shaft 3 and when the counter shaft is rotating in a counter clockwise direction, the shaft 3 will be driven in a counter clockwise direction for rewinding the spring 13, so that 60 it can be reset.

To rotate the counter shaft 33 a sliding

clutch section 39 is keyed on the driven shaft 11 for rotation therewith and is adapted to be moved forward into locking engagement with the rigid clutch section 40 carried by the gear 31. A collar 41 is rotatably mounted upon the clutch section 39 and fits in a groove 42 formed therein and is connected to a leaf spring 43 which is bolted as at 44 to a lug 45 connected to one side of the casing 2 and the leaf spring 43 normally tends to hold the clutch section 39 out of engagement with the rigid clutch section 40. The inner end of the sliding rod 27 engages the collar 41 when the same is thrown rearward by an arm 21, which operates the sliding clutch section 19, so that when the clutch section 19 is thrown 70 into locking engagement with the rigid clutch section, the sliding clutch section 39 carried by the driven shaft 11 is positively prevented from going into engagement with the rigid clutch section 40 keyed to the gear 75 31. When the sliding clutch section 40 is actuated, the collar 41 will engage the inner end of the sliding rod 27 and push the same forwardly and disengaging the clutch sections 19 and 20. The foot pedal (not 80 shown) for actuating the sliding clutch section 19 is spring pressed and when the foot of the operator is removed from the pedal, the same automatically returns to its normal position and also tends to automatically 85 disengage the clutch sections 19 and 20.

A bell crank 46 is pivotally secured by means of a pivot pin 47 which passes through the angle thereof into a projecting lug 48 carried by the side of the casing 2, and has 100 a foot 49 pivotally secured thereto which bears against the outer surface of the coil spring 13. The opposite end of the crank 46 has a pivoted link 50 which is connected to a coil spring 51, which is in turn connected to an arm 52 carried by the collar 41, which is rotatably carried by the sliding clutch section 39 and it will be seen that when the spring 13 is unwound and the same has expanded, the end of the bell crank 46 carrying the foot 49 will be pressed downward which will force the other leg of the bell crank inward and overcome the tension of the leaf spring and throw the clutch section 19 out of engagement with the clutch 110 20 and the clutch 39 into engagement with the clutch 40 carried by the gear 31.

A suitable spur gear 54 is carried by the free end of the driven shaft 11 which projects out of the casing 2 and this gear is 115 adapted to be connected with the crank shaft of the engine (not shown) by gears or a sprocket and chain (not shown) so that when the driven shaft is being rotated the same will, through the medium of the gears 120 (not shown) turn the engine over.

A suitable crank 55 is detachably secured to the front end of the driving shaft 3, which projects out of the front of the casing, so that the shaft can be rotated to initially wind up the spring 13. After the spring 13 has been once wound up, the crank can be taken off of the shaft 3, as then the operation of the improved starter is entirely automatic, or the crank can be carried 10 around for emergency.

In operation of the improved device, when it is desired to start the engine, the foot pedal which is not shown, is pressed downward which rocks the stub shaft 24 15 which carries the arm 21 and throws the movable clutch section 19 in locked engagement with the clutch section 20 and at the same time, the sliding arm 27 is moved forward which releases the pawl 15 from engaging the ratchet wheel 17, through the medium of the enlarged end 30^a thereof which will allow the spring 13 to rotate the driving shaft 3 which has been locked 20 through the medium of the sliding clutch sections 19 and 20 to the driven shaft 11, which will in turn, turn over the internal combustion engine (not shown) and start the same. After the engine has been started by means of the spring 13, the same will 25 have become unwound and will therefore be enlarged and the same will press downward on the foot 49 carried by the bell crank 46 which will draw the other end of the arm toward the coil spring 13 and overcome the tension of the leaf spring 43 and draw the 30 sliding clutch section 39 carried by the driven shaft 11 into engagement with the rigid clutch section 40 carried by the gear 31 and will rotate the gear 31 which will in turn rotate the counter-shaft 33 and the same will 35 through the medium of the gears 35, 36 and 38 drive the driving shaft 3 in a direction opposite to which the shaft is first rotated and rewind the spring 13, so that the starter 40 will be automatically reset. While the clutch sections 39 and 40 are becoming engaged the clutch sections 19 and 20 are automatically being disengaged through the 45 medium of the collar 41 engaging the sliding arm 27.

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that various 55 minor changes in details of construction, proportion and arrangement of parts, may be resorted to, when required, without sacrificing any of the advantages of my invention, as set forth.

What is claimed is:—

1. An engine starter comprising a driving shaft, a driven shaft, means connecting the driven shaft with the crank shaft of an internal combustion engine, a sliding clutch section carried by the driving shaft, a rigid clutch section carried by the driven shaft, 65 spring means associated with the driving shaft for rotating the same, a ratchet wheel on said shaft, a pawl engaging said ratchet to prevent the rotation of the shaft in one direction, an arm connected to said sliding clutch for moving the same into the rigid clutch section carried by the driven shaft, and a sliding arm pivotally connected to the arm carried by the sliding clutch for engaging said pawl to disengage the same from 70 the ratchet wheel, whereby upon movement of said arm carried by the sliding clutch, the driving and driven shafts will be connected for movement together and the pawl will be released from the driving shaft, so that the 75 spring can rotate the same.

2. An engine starter comprising a driving shaft, a driven shaft, means operatively connecting the driven shaft with the crank shaft of an internal combustion engine, spring 80 means for rotating said driving shaft, means for preventing the rotation of the driving shaft in one direction, means for locking the driving and driven shafts together and for releasing said locking means engaging 85 the driving shaft, a counter-shaft extending parallel to and in spaced relation to the driving and driven shafts, means operatively connecting the counter-shaft with the driving shaft, a gear rotatably mounted 90 upon the driven shaft for independent movement, means operatively connecting said gear with the counter-shaft, a sliding clutch section keyed to said driven shaft, a rigid clutch section carried by said gear rotatably mounted on the driven shaft, a leaf 95 spring normally holding said sliding clutch section out of engagement with the rigid clutch section, a bell crank pivotally secured to the bottom of the casing, a presser foot 100 pivotally carried by one end of the bell crank and engaging the outer side of the coil spring, and means connecting the free end of the bell crank with the leaf spring, so that when the spring expands caused by 105 the unwinding thereof, said bell crank will overcome the tension of the leaf spring and interlock the sliding clutch section and rigid clutch section carried by the rotatable gear together, as and for the purpose specified. 110

3. An engine starter comprising a driving shaft, a driven shaft, means connecting the driven shaft with the crank shaft of an internal combustion engine, spring means connected to the driving shaft for rotating 115 the same, means engaging said driving shaft 120

to hold the same against rotation in one direction, means interlocking the driving and driven shafts together for synchronous movement, a counter-shaft extending parallel with said driving and driven shafts, means connecting the counter-shaft with the driving shaft, a gear notably mounted upon the driven shaft and operatively connected with the counter-shaft, and means for 10 engaging the periphery of the spring for

locking and unlocking the rotatable gear on the driven shaft with said driven shaft, as and for the purpose specified.

In testimony whereof I affix my signature in presence of two witnesses.

ROBERT L. HOGG.
